E. W. HOWE,
BRUSH BLOCK BORING MACHINE,
APPLICATION FILED MAY 10, 1921.

Patented June 20, 1922.

2 SHEETS—SHEET 2.

UNITED STATES PATENT OFFICE.

EDWARD W. HOWE, OF TOLEDO, OHIO.

BRUSH-BLOCK-BORING MACHINE.

1,420,104.

Specification of Letters Patent. Patented June 20, 1922.

Application filed May 10, 1921. Serial No. 468,407.

To all whom it may concern:

Be it known that I, EDWARD W. HOWE, a citizen of the United States, and resident of Toledo, in the county of Lucas and State of Ohio, have invented certain new and useful Improvements in Brush-Block-Boring Machines, of which the following is a specification.

My invention relates to brush block boring machines and it is my purpose to generally improve the construction of such machines whereby compact assembly of parts, ease of operation, and consequently greater speed in production is obtained, my invention consisting in the novel features of construction, combination and arrangement of parts as will be hereinafter more fully disclosed and claimed.

My inventive idea is capable of embodiment in various mechanical structures, one of which is shown in the accompanying drawings, but it is to be understood that the structure illustrated is merely intended to disclose the essential features of my invention in a preferred form and that its scope is as defined in the appended claims.

In the drawings, wherein like characters of reference denote corresponding parts in the different views:

Figure 1 is a side elevation of a brush block boring machine constructed in accordance with my invention, with certain parts removed.

Figure 2, an end view of the same.

Figure 3, a plan view,

Figure 4, an end view opposite to Figure 2,

Figure 5 a fragmentary side elevation showing the parts omitted from Figure 1; and

Figure 6 an enlarged detail section of one of the drill spindle supports.

Referring now to the drawings in detail, it will be observed that the movable parts of my machine are mounted upon a frame or support 10 which includes a base portion 11 having a standard 12 rising from one end thereof. Upon the upper face of the base portion is a longitudinally extending guide flange 13 having formed therein a T-slot 14, while between the base and the standard 12 is a housing 15 adapted to receive an electric motor 16 or other suitable power appa-

ratus for operating the driven parts of the machine.

Secured to one side of the standard 12 is a plate 17 which is bored at 18 to receive a pin 19. Between a pair of shoulders on the pin and in the bore, respectively, is a coiled expansion spring 20 exerting an influence urging a tapered end 21 of the pin normally beyond the end of the plate through which it projects. A nut on the opposite end of the pin provides an adjustable means of limiting movement of the pin with respect to the plate, while the plate itself is adjustable with respect to the standard 12 by reason of a slot 22 through which the bolts 23 which secure it to the standard are passed.

Carried by and extending through the standard 12 and horizontally aligned with the pin 19 is a pair of spindles 24, each of which carries, to one side of the standard, a drill chuck 25, and to the other side of the standard a pulley 26. A belt 27 passes over a pulley 28 on the motor spindle and over the pulleys 26 whereby the drill chucks may be rotated, and an idler pulley 29 is carried by a bracket 30 adjustably secured to the standard whereby the tension of the belt may be regulated.

Each of the spindles 24 is mounted for longitudinal yielding movement as indicated in Figure 6 of the drawings, being journaled in suitable bearings 31 within a bushing 32 which in turn is suitably supported within the standard 12. A plate 33 carried by the bushing and adapted to abut the standard limits movement of the bushing in a direction in which it is normally urged by a coiled spring 34, but said bushing may be moved in an opposite direction against the spring as is obvious. Secured to each bushing is a bracket 35 which serves as both a drill guide and depth gauge.

A block 36 has its under face channeled to receive the guide flange 13 and a pair of bolts 37 passing through this block and having their heads received in the T-slot 14 provide a means for retaining the block in proper relation to the guide flange, at the same time permitting the block to be moved or adjusted along said flange.

A shaft 38 passing through the block 36 provides a means of securing an anti-friction bearing 39 to either side of the latter

whereby a frame-like arm 40 is mounted on the block for swinging movement, towards and away from the standard 12. The frame-like arm 40 is of substantially rectangular shape and is bifurcated at its lower end so as to straddle the block 36, the arms of the bifurcation receiving the bearings 39.

At its upper end the arm 40 is provided with an offset or extension 41 within which 10 is journaled in suitable anti-friction bearings 42 a shaft 43. A collar 44 on the shaft abuts one side of the extension 41 and a nut 45 is threaded on the shaft and abuts the other side of the extension whereby the freedom of rotation of the shaft may be varied. 15 Adjacent to the collar 44 the shaft is provided with a bifurcated head 46 between the arms of which is clamped a shaft 47 which extends longitudinally of the machine and at its end adjacent the standard 20 12 carries a frame 48 rotatably supporting three vertically disposed shafts 49, 50 and 51, the first of which is normally disposed in alignment with the pin 19 while the latter two are respectively normally disposed 25 in alignment with the pair of drill chucks 25. A hole is formed transversely through both the upper and lower end of each shaft 49, 50 and 51 and each hole slidably receives 30 a rod 52, held in any slidably adjusted position by a set screw 53. A block 54 is carried by each shaft 52 adjacent the end of the latter disposed towards the arm 40 and connecting these blocks are link members 35 55. Carried by each upper and lower pair of rods 52, upon their ends disposed towards the standard 12, is a plate 56 having means 57 associated therewith for holding either a brush block 59 or a pattern plate 40 60. As shown, the pattern plate is held by the plate 56 supported from the vertical shaft 49, while a pair of brush blocks 59 are held by the plates 56 supported from the vertical shafts 50 and 51.

45 The pattern plate 60 has holes therein located and spaced in a manner in which it is desired to form brush wisp-receiving holes in the brush blocks 59, and since the manner of mounting the plates 56 renders them 50 movable in unison, successive alinement of the holes in the pattern plate with the tapered end of pin 19 and movement of the brush blocks toward the drills carried by the chucks 25 will result in holes being 55 drilled in the brush block corresponding to the arrangement of the holes in the pattern plate. After the brush blocks have been drilled they are removed from the machine and the wisps subsequently secured in the 60 holes in any well known or desired manner.

By having the pin 19 spring pressed towards the pattern plate the proper alinement of the tapered end thereof with the holes in the pattern plate may be obtained 65 before the brush blocks are brought into

contact with the drills, thus reducing the possibility and chance of drilling erroneously located holes in the brush blocks, and if too great a pressure of the brush blocks against the drills be exerted the springs 20 70 and 34 will permit the pin 19 and chucks 25, respectively, to yield, the members 35 in any event limiting the depth of the holes drilled in the brush blocks.

By means of the blocks 36 the pattern plate 75 and brush blocks together with their supporting structure are movable bodily toward and away from the drills and the guide pin 19, and by means of the pivoted connections between the block 36 and arms 40, and between 80 the shaft 43 and arm 40 and shaft 47, respectively, and between shafts 49, 50 and 51 and the frame 48, practically any desired adjustment of the brush blocks and pattern plate with respect to the drills and guide pin 85 may be had. Furthermore, it is clear that the number of brush blocks possible to be drilled from a single pattern plate is indefinite, and at the same time the machine is of simple and comparatively inexpensive construction as well as strong and durable and its parts are compactly arranged.

In the drawings I have illustrated the pattern plate 60 as secured to its plate 56 in the same manner that the brush blocks are secured to their respective plates, but as the pattern plate is seldom removed it may be secured in various manners, as for instance, by screwing it fast to plate 56, or by fastening it to a block and then in any desired manner securing the block to the plate, or the same result may be accomplished in any other manner, the specific means for so doing constituting no essential part of my invention.

Having thus described my invention, what I claim is:—

1. A brush block boring machine comprising a base having a drill mounted thereon, and brush block holding means mounted on the base and including an arm pivoted for swinging movement in a plane parallel with respect to the axis of the drill, a shaft carried by said arm and disposed parallel to the pivotal axis thereof, said shaft being rotatably adjustable with respect to the arm, a rotatably adjustable shaft carried by and disposed at right angles to said first mentioned shaft, a frame carried by said second mentioned shaft, and means carried by said last shaft upon which the brush block is secured.

2. A brush block boring machine comprising a base having a drill mounted thereon, and brush block holding means mounted on the base and including an arm pivoted for swinging movement in a plane parallel with respect to the axis of the drill, a rotatably adjustable shaft carried by the arm and disposed parallel to the pivotal axis thereof, a

shaft carried by and disposed at right angles to said first mentioned shaft, said second mentioned shaft being rotatably and longitudinally adjustable with respect to the first 5 shaft, a frame carried by said second mentioned shaft, and means carried by the frame upon which the brush block is mounted.

In testimony whereof I hereunto affix my signature in the presence of two witnesses.

EDWARD W. HOWE.
